Patented July 24, 1973

227,900

ELECTRONIC CONTROL CONSOLE

Anthony P. H. Chan, Los Altos Hills, and Hugh John Hall, Los Altos, Calif., assignors to Syntex Corporation, Apartado, Panama

Filed Aug. 16, 1972, Ser. No. 281,197

Term of patent 14 years

Int. Cl. D14—02

U.S. Cl. D26—5 C

Fig. 1

Fig. 2

Fig. 3

Fig. 4

Fig. 5

Fig. 6

FIG. 1 is a perspective view of an electronic control console showing our new design;

FIG. 2 is a front elevational view thereof, the keyboard being fragmentarily shown for ease of illustration;

FIG. 3 is a top plan view thereof;

FIG. 4 is a left side elevational view thereof;

FIG. 5 is a right side elevational view thereof; and

FIG. 6 is a rear elevational view thereof.

We claim:

The ornamental design for an electronic control console, as shown and described.
